UNITED STATES PATENT OFFICE.

ALFRED M. THOMAS, OF FORT MORGAN, COLORADO.

ENLARGING OR REDUCING PHOTOGRAPHIC PRINTER.

Application filed October 16, 1922. Serial No. 594,833.

To all whom it may concern:

Be it known that I, ALFRED M. THOMAS, a citizen of the United States, residing at Fort Morgan, in the county of Morgan and State of Colorado, have invented certain new and useful Improvements in Enlarging or Reducing Photographic Printers, of which the following is a specification, reference being had to the accompanying drawings.

10 This invention relates to machines for printing photographs, and particularly to those machines in which the image to be printed is enlarged or reduced with relation to the size of the original negative.

15 Machines of this character embody ordinarily a table upon which the sensitized paper is disposed, a source of illumination, a lens which is disposed between the table and the source of illumination, and a negative carrier disposed between the source of illumination and the lens. In the greater number of enlarging photographic projectors of this character the lens has to be focused by hand as well as adjusted for 20 producing the desired enlargement or reduction.

25 The general object of my invention is to provide means for automatically focusing the lens as the negative and lens are moved toward or from the table upon which the sensitized paper is disclosed.

30 A further object is to provide manually operable means whereby very fine focusing adjustments may be made or the lens shifted 35 slightly out of focus if desired.

35 A still further object is to provide means whereby the apparatus is adapted to produce prints reduced with relation to the original negative.

40 Still another object is to provide an automatic focusing device of this character which is very simple, which cannot readily get out of order, and in which a relatively wide range of focusing movement is provided for.

45 Other objects have to do with the details of construction and arrangement of parts as will appear more fully hereinafter.

50 My invention is illustrated in the accompanying drawings, wherein:—

55 Figure 1 is a side elevation partly broken away of my improved photographic printing machine;

60 Figure 2 is a fragmentary front elevation, the lamp hood or lantern being in section;

65 Figure 3 is an enlarged front elevation of

the automatic focusing mechanism, the negative support, the lamp hood and the bellows being removed;

60 Figure 4 is a section on the line 4—4 of Figure 3;

Figure 5 is a section on the line 5—5 of Figure 3;

65 Figure 6 is a fragmentary longitudinal section on the line 6—6 of Figure 3;

Figure 7 is a fragmentary vertical section on the line 7—7 of Figure 2;

70 Figure 8 is an enlarged sectional view through the clamping members 78 and 79.

75 Referring to these drawings, 10 designates a base upon which is erected an upright or column section 11, which at its upper end is provided with an upwardly projecting pin 12. Mounted upon the upright 11 is the cross piece 13, which by means of a bracket 14 supports a transverse beam 15. Hinged to this transverse beam 15 is the table 16, which may be of any suitable form or construction and is shown as supported by means of a leg 17. A diagonally extending 80 brace 18 extends down to the base 10 and is supported by a cross piece or foot 19. The leg 17 is illustrated as hinged to the table 16 so as to permit the table to be folded down. Any suitable table arrangement may 85 be used in place of that illustrated.

85 Detachably mounted upon the upright 11 is a column, which is designated generally 20. This column is formed of a medially disposed beam or member 21, to which, as 90 illustrated in Figures 1 and 5, there is attached a metallic clip 22 formed at its rear end with an eye 23 embracing the pin 12. At its lower end the member 21 is formed with a socket 24, as illustrated in Figure 7, 95 and extending upward through the member 13 and through the member 15 is a pin 25 which engages in said socket, there being an angle iron 26 connecting the members 13 and 15 through which this pin 25 passes. Thus 100 the column 20 is vertically movable with relation to the upright 11 and is also detachable from the upright 11. The column 20 comprises the vertical member 21, to the rear edge of which are attached the vertically and laterally projecting members 27 and to these members 27 are attached the laterally disposed casing members 28 which extend beyond the members 27 so as to form a 105 weight compartment 29. These members may be connected to each other in any suitable manner.

110

The upper end of the column is formed by a member 30 carrying the grooved wheels or pulleys 31, over which passes a cable 32, one end of this cable being connected to a counter-weight 33 moving within the weight compartment 29. The opposite end of this cable 32 is connected to the slide, designated generally 34, this slide being formed of a rear member 35 and two guides 36 attached to the front of the member 35 are spaced from each other. Attached to the member 35 are inwardly projecting guides 37 which move in the space between the upright 21 and the side pieces 28 and are guided thereby. Metal facing strips 39 are disposed upon the outer faces of the upright 21 and the side pieces 28. As illustrated in Figure 4, the members 37 are attached to the guides 36 by angular metallic strips 40 which are attached to the inside faces of the members 36 and which extend inward on each side of the upright 21 and are attached to the guides 37. One of these strips extends inward nearly to the members 27 and is attached to a slide 41 operating between the adjacent member 27 and the guide strip 42. Thus it will be obvious that the slide 34 may move up and down the full length of the column. Mounted in the space between the members 36 is a slide 43. This slide is held in place between the members 36 by means of the strips 44 attached to the member 36 and extending over the margins of the slide 43. The upper end of the slide 34 is attached to the cable 32 in any suitable manner. The slide 43 which carries the lens is shifted with relation to the slide 34 which carries the hood and the negative holder by means of two levers 45 which are pivoted at 46 upon transverse metallic strips 47 mounted upon the faces of the members 36. These two levers 45 cross each other at their lower ends and their inner edge faces are given a certain curvature to exert a camming action upon rollers 48 mounted upon the outer extremities of a T-shaped member 49 which is pivoted to the face of slide 43, as at 50. The T-shaped member 49 is laterally shiftable upon its pivot 50 and the rollers 48 contact with the inner slightly curved faces of the levers 45 so that as the outer ends of the levers are depressed the inner ends will move toward each other and will exert a lifting force upon the rollers 48 and upon the slide 43, and that reversely as the upper ends of the levers 45 move toward each other the lower ends below the pivot points 46 will expand and permit the rollers 48 to move down and the slide 43 to move down. This movement of the levers 45 is secured by links 51 which are pivoted to the upper ends of levers 45 and extend upward convergently and are pivoted to an outwardly and laterally projecting bracket 52 which is attached to the member 21 in any suitable

manner, this bracket 52, as illustrated in Figure 1, projecting outwardly and then laterally so as to provide a space for the cable 32.

Below the intersecting ends of the levers 45 the slide 36 has an outwardly projecting, longitudinally extending guide 53 and on each side of the guide the slide 43 has the angularly disposed guide strips 54. Disposed on each side of the guide rib 53 are the plates or metallic strips 55 whose inner ends are angularly bent to engage beneath the guide flanges 54. These strips or plates 55 extend out beyond the guide rib 53, and disposed between the outer ends of these strips is a filler block 56, the strips or plates 55 being attached to this filler block by transversely extending screws, bolts or other like devices 57. The plates may be contracted upon the guide rib 53 or expanded with relation thereto so as to increase or decrease the frictional engagement of the strips 55 with the guide rib 53 by means of the transversely extending bolt 58 to which a wing nut 59 is attached. The outer ends of the strips or plates 55 are angularly bent away from each other and then extended outward to partially embrace a lens support 60 carrying the lens 61 therein.

It will be seen that the member 55 is thus longitudinally shiftable with relation to the slide 43 and that this slide 43 in turn is longitudinally shiftable with relation to the slide 34. The lens carrier 60 is vertically adjustable by means of a hand lever 62 which is pivoted at one end to a lug 63 projecting downward from the lower end of the slide 43, this lever being connected by a link 64 to one of the sliding plates 55. These sliding plates have frictional engagement with the tongue or rib 53 so that the lens carrier will be frictionally held in any adjusted position and by shifting the lever 62 upward or downward, the lens carrier may be shifted through a slight range and very delicately.

Detachably mounted upon the slide 34 at the upper end thereof is a negative holder and hood support, designated generally 65, comprising a rectangular frame formed to support above it the domical hood 67 and support within this domical hood a plurality of incandescent lamps 68. The slide 34 also carries upon it the bracket 69 which supports at its upper end an electric blower and exhaust fan 70 which is connected by any suitable tubing to an outlet pipe 71 extending from the upper end of the dome. The frame 65 is formed with air inlet ports 72 which are angular so as to prevent the light from escaping from the frame but permit the inlet of air. The lower portion of the frame 65 is attached to a bellows 73 whose lower end in turn is connected to the lens box or support 60. The frame 65 is

formed with an opening for the insertion of a negative carrier 74 of any suitable construction which is, of course, disposed below the lamps 68 and which has a handle 75 whereby it may be readily inserted into the frame 65 or removed therefrom.

It will be obvious now that with this construction automatic means is provided for accurately focusing the projected image of 10 the negative onto the table 16 and onto the sensitized sheet supported thereby. When it is desired to make an enlargement the slide 34 is shifted by hand up or down its guideways on the column 20 so that the 15 proper sized image is projected upon the table 16. The further away the lens 61 is from the table, the larger will be the enlargement, and the nearer this lens 21 to the table, the smaller will be the enlargement. 20 As the slide 34 moves downward the levers 45 will move toward each other at their upper ends and thus permit the T-shaped member 49 to descend. This permits, of course, the descent of the slide 43 relative 25 to the slide 34, thus expanding the bellows and correctly focusing the lens 61 upon the table. As the slide 34 is moved upward, however, the upper ends of the levers 45 will be caused to move away from each other 30 by the links 51 so that the inner edges of the lower ends of these levers will lift up on the rollers 48, thus lifting the slide 43 with reference to the slide 34 and compressing the bellows. Thus the focusing of 35 the lens 61 is absolutely automatic and it is only necessary for the operator to shift the slide 34 to a position where the correct enlargement will be had in order to secure the accurate focusing of the lens.

40 In some cases the photographer or printer places the negative in the negative holder with the film side downward and in other cases with the film side upward, and this requires a slight difference in focusing. 45 This is provided for by shifting the lens carrying slide relative to the slide 43 a slight amount by means of the lever 62. This lever 62 may also be used where the sensitized paper is not disposed upon the table 16 but 50 is put in a frame, making a slight difference in elevation. It may be also used for throwing lens 61 slightly out of focus in case it is desired to soften the image.

55 One of the principal features of this invention is the provision of means whereby reductions may be made as well as enlargements, and in order to make a reduction it is necessary to increase the distance between the plate and the table 16 over that ordinarily used for producing enlargements, and it is for this purpose that I have so mounted the column 20 upon the supporting frame that the column 20 may be lifted a predetermined amount and held in its lifted position whenever desired. To this end I have

mounted upon the member 15 a vertical iron 76 having a plurality of apertures 77, this member 76 being in spaced relation to the confronting face of the column, and I have formed the lower end of the vertical member 70 21 with one or more apertures adapted to register with the apertures 77 so that a screw-driver or other tool may be inserted through one of the apertures 77, engaged with an aperture in the face of the beam 21, 75 then the tool will be pressed so as to raise the column.

In order to hold the column raised relative to the table 16, I attach to the member 15 in one side a U-shaped guide 78, and 80 pivot within this guide a clamping member 79 having an aperture through which a rod 80 passes, this rod being pivoted upon a bracket 81 attached to the member 21. When this clamping member 79 is at right 85 angles to the rod 80 it will permit the rod 80 to be raised or lowered, but when at less than a right angle it will bind upon the rod 80 and hold this rod from downward movement. Thus it will be seen that the column 90 may be raised any necessary amount by the tool inserted through the apertures 77 and that then when the column is released the rod 80 will be engaged by the clamp 79 and the column held in a raised position. When it is 95 desired to release the column, the clamping member 79 is to be shifted to a position at right angles to the rod 80 and the tool used to lower the column relative to the table 16. As before remarked, this adjustment permits of reductions being made, which reductions are impossible with any other printing machine known to me, which printing machine is capable of making enlargements. 100

I have found in actual practice that it is particularly desirable to use a plurality of lamps 68 in place of the one lamp generally used, as this distributes the heat over the face of the negative. If one lamp was used of sufficient candlepower to give the requisite 105 illumination, the heat given off by this lamp would be so great that there would be liability of cracking the negative or otherwise injuring it, as this heat would be concentrated at one point on the negative. By 110 providing a plurality of lamps, however, this concentration of heat upon the negative is prevented. These lamps, however, would tend to crack the negative or otherwise injure it were it not for the fact that there is 115 a constant indraft of cool air through the apertures 72, this cool air passing upward and being drawn out by the exhaust fan 70. The cool air is admitted through the apertures 72 immediately above the negative holder 120 74 and all the heat is carried away from the negative, thus preventing any cracking or other injury to the negative. I have found in actual practice that a much more effective result is secured by exhausting the air 125 130

from the interior of the lamp dome 67 than by forcing in cold air through this dome and that by sucking the hot air out of the dome there is much less likelihood of the air in the 5 interior of the dome becoming highly heated.

It will be seen that the engagement of the column by the pins 25 and 12 permits the column to be raised and lowered without permitting the column to tip with reference 10 to the base or to be dislodged from the base unless it is desired to entirely remove the column from the base for transportation or for packing. The arms 45 may be longer if desired or shorter without departing from 15 the spirit of the invention, but any lengthening or shortening of the arms will require that a different curvature be given to the inner edge faces of these arms than that illustrated in the drawings. By making the 20 arms relatively long and decreasing the curvature of these edge faces, the range of movement of the slot 43 may be correspondingly increased. It is, of course, obvious that the arms, when the upper ends are 25 shifted to their minimum distance from each other, must at all times prevent the complete descent or too great descent of the slide 43. The member 49 which supports the rollers 48 is preferably pivoted at 30 50 in order to permit this member to shift laterally and compensate for any minute irregularities in the inner edge faces of the arms 45. This member 49, therefore, acts as an evener and both rollers 48 will at all times 35 engage the inner edge faces of the adjusting levers 45.

The action of the levers 45 is such that a very rapid increase in the ratio of movement of the lens relative to the negative 40 is secured as the slide 36 moves downward. My construction secures a very wide range of movement of this slide, so that the slide may be moved down beyond the point where an image is printed on the sensitized paper 45 of the same size as the negative and thus considerably reduced prints may be secured. In making enlargements it is necessary that the slide 36 be shifted downward until the image of the negative has been reduced to 50 the extent required. At this point, however, the image while of the size required, that is of the reduction required, will not be well defined and will be out of focus and it is necessary in order to secure proper definition that the negative shall be raised to a greater or less degree until this focus is 55 secured. It is for this purpose that I have provided the means illustrated in Figure 7 whereby the column as a whole may be raised with reference to the table so as to 60 raise the negative holder with relation to the table. This does not affect the lens, as the lens when it is relatively close to the paper requires considerable movement in order to 65 in any way affect the image.

I do not wish to be limited to the particular means illustrated for relatively shifting the negative carrier and the table, as other means might be used for this purpose without departing from the spirit of 70 the invention, but I have particularly devised this means for the reason that it is simple, the column with the negative holder and other parts is held firmly by the clamp 79 in any desired position, and I have found in actual practice that the column may be raised a very small fraction of an inch in order to secure this proper focus. Furthermore, it is desirable to make the column 20 75 separate from the table 13 and the post 11 80 so that the column can be removed with the post 11 for packing purposes. Inasmuch as the column is to be made removable for transportation, it is obvious that it is a relatively simple matter to provide means for 85 adjusting the column and thus secure the result called for.

While I have illustrated details of construction and arrangements of parts which I have found to be particularly desirable 90 and particularly effective in actual practice, I do not wish to be limited to the exact details, as obviously these might be changed in minor respects without departing from the spirit of the invention as defined in 95 the appended claims.

I claim:—

1. An enlarging or reducing printer including a table, a vertical support operatively mounted in connection with the table 100 for vertical movement with reference thereto, a negative carrying support vertically movable on the vertical member, a lens carrier independently slidable upon the support, a bellows disposed between and connected to the support and carrier respectively, means automatically decreasing the distance between the lens carrier and the negative support as the negative support is moved away from the table and increasing 105 this distance as the negative support is moved toward the table, and means whereby the vertical member may be vertically shifted with reference to the table.

2. An enlarging and reducing printer including a table having a vertical portion, a column mounted upon the vertical portion of the table for vertical movement toward or from the table, a negative carrying support mounted for vertical movement on the column, a lens carrier independently slidable vertically upon said negative support, a bellows disposed between and connected to the support and carrier respectively, means automatically decreasing the distance between the lens carrier and the negative support as the negative support is moved away from the table and increasing this distance as the negative support is moved toward the table, and means whereby the column may be ver- 115 120 125 130

- tically adjusted with reference to the table and held in its vertically adjusted position.
3. An enlarging or reducing photographic printer including a table, a vertical column mounted upon the table, a slide mounted upon the column, a counter-weight for the slide, a negative support, a lantern carried upon the slide and movable therewith toward and from the table, a second slide mounted for vertical movement within the first named slide, a lens carrier mounted on the second named slide, a bellows disposed between and connected to the lens carrier and to the lantern and negative support, means for automatically decreasing the distance between the lens holder and negative support as the negative support is moved away from the table and increasing the distance as the negative support is moved toward the table including a pair of levers pivotally mounted upon the first named slide and having their lower ends intersecting each other, links pivotally connected to the ends of said levers and extending convergently upward and pivotally connected to said column, and a member having rollers each engaging the inside edge face of one of said levers, said member being connected to the second named slide.
- 30 4. An enlarging or reducing photographic printer including a table, a vertical column mounted upon the table, a slide mounted upon the column, a counter-weight for the slide, a negative support, a lantern carried upon the slide and movable therewith toward and from the table, a second slide mounted for vertical movement within the first named slide, a lens carrier mounted on the second named slide, a bellows disposed between and connected to the lens carrier and to the lantern and negative support, means for automatically decreasing the distance between the lens holder and negative support as the negative support is moved away from the table and increasing the distance as the negative support is moved toward the table including a pair of levers pivotally mounted upon the first named slide and having their lower ends crossing each other, the inside faces of the lower ends of the levers being concavely curved, links pivotally connected to the outer ends of the levers and extending convergently upward and being pivotally connected to the upper end of the column, and a member pivotally mounted upon the second named slide and carrying rollers bearing against the inner faces of the lower portions of said levers.
- 50 5. An enlarging and reducing photographic printer including a table, a vertical column having laterally spaced slideways, a slide disposed against the face of the column and having portions entering said slideways, and guided thereby, means mounted on the column for counter-weight-
- ing the slide, the slide being formed with a vertical guideway, a second slide disposed within the vertical guideway and independently movable with relation to the first named slide and carrying guideways adjacent its lower end, a lens carrier mounted between the last named guideways and vertically adjustable therebetween, a pair of levers pivoted to the first named slide and having their lower ends extending downward and across each other and over the face of the second named slide, the lower ends of the levers being curved inward, said levers extending upwardly and divergently, links pivoted to the upper ends of the levers and extending convergently upward and being pivotally connected to the column adjacent its upper end, a member mounted upon the second named slide and carrying rollers bearing against the inner edge faces of the two levers, and a lever pivotally mounted upon the second named slide and operatively connected to the lens carrier whereby the lens carrier may be vertically shifted.
6. An enlarging and reducing photographic printer including a table, a vertical column having laterally spaced slideways, a slide disposed against the face of the column and having portions entering said slideways and guided thereby, means mounted on the column for counter-weighting the slide, the slide being formed with a vertical guideway, a second slide disposed within the vertical guideway and independently movable with relation to the first named slide and carrying guideways adjacent its lower end, a lens carrier mounted between the last named guideways and vertically adjustable therebetween, a pair of levers pivoted to the first named slide and having their lower ends extending downward and across each other and over the face of the second named slide, the lower ends of the levers being curved inward, said levers extending upwardly and divergently, links pivoted to the upper ends of the levers and extending convergently upward and being pivotally connected to the column adjacent its upper end, a member mounted upon the second named slide and carrying rollers bearing against the inner edge faces of the two levers, a lever pivotally mounted upon the second named slide and operatively connected to the lens carrier whereby the lens carrier may be vertically shifted, and means whereby the column may be vertically shifted with relation to the table and held in its adjusted position.
7. An enlarging and reducing photographic printer including a work table, a column associated therewith and mounted for vertical adjustment with reference thereto, a negative carrying support mounted

for vertical movement on the column, a lens carrier independently shiftable vertically upon the support, a bellows disposed between and connected to the support and carrier respectively, means for automatically shifting the lens carrier upon the support as the support is vertically adjusted to secure the proper focusing of the lens on the table, means for raising the column 10 with reference to the table including a fulcrum member mounted upon the table and adapted to act as a fulcrum for a tool, means on the column forming an engaging point for said tool, a rod vertically movable with the column, and a clamp mounted upon the table and adjustable to engage said rod and automatically hold it from downward movement, said clamp being movable to a position to permit downward 20 movement of the rod and column.

8. A photographic enlarging and reducing printer including a base portion having a vertically extending member, an upwardly extending member having an upwardly extending pin and the base portion in front of said member having a downwardly extending socket, a column normally resting upon said base portion and carrying at its lower end a downwardly extending pin insertable into said socket, the column having a recess in its rear face into which the vertical member extends and the column having a sleeve fitting said pin at the upper end of said vertical member, the column being 30 formed to provide a medial vertical portion and two side vertical portions defining slide-ways open upon the front of the column, a slide resting against the face of the column and having guides projecting into said slide-ways, a counter-weight moving in the recessed rear face of the column and having a cable passing over the top of the column and operatively engaging said slide, there being pulleys in the top of the column over 40 which said cable passes, the base of said slide being formed with a vertical guideway, a second named slide disposed in said guideway for vertical movement with reference to the first named slide, a lens support 45 slidably mounted upon the second named slide for vertical movement, means mounted upon the second named slide and connected to the lens support whereby the lens support may be vertically moved with 50 reference to the second named slide, a lantern, a negative support mounted upon the first named slide, a bellows connecting the lens support and said negative and lantern

support, means for automatically focusing the lens as the first named slide is moved toward or from the table comprising levers pivoted upon the first named slide at each side thereof, said levers extending downward and crossing each other and having their inner faces slightly curved, a T-shaped member pivotally mounted upon the second named slide and having rollers at the ends of the cross arm of the T resting against the edge faces of said levers, and links pivotally connected to the upper ends of said levers and pivotally connected to the upper end of the column.

9. A photographic enlarging and reducing printer including a paper support, a negative carrier movable toward or away from the paper support, a lens carrier independently movable toward or from the paper carrier, a bellows disposed between and connected to the negative support and the lens carrier respectively, means automatically decreasing the distance between the lens carrier and the negative support as the negative support is moved away from the paper support and increasing the distance as the lens carrier is moved toward the paper support to thereby automatically focus the lens upon the paper support at all times, and independent means for bodily adjusting the paper support and the negative carrier toward or from each other.

10. A photographic enlarging and reducing printer including a sensitized paper support, a longitudinally extending member, a negative carrying support longitudinally shiftable on the longitudinal member, a slide mounted for longitudinal movement upon the negative support, a lens carrier mounted upon said slide, a bellows disposed between and connected to the negative support and the lens carrier respectively, means for automatically decreasing the distance between the lens carrier and the negative support as the negative support is moved away from the sensitized paper support and automatically increasing this distance as the negative support is moved toward the paper support, and independent manually operable means for increasing or decreasing the distance between the negative support and the sensitized paper support without affecting the distance between the lens carrier and the negative support.

In testimony whereof I hereunto affix my signature.

ALFRED M. THOMAS.
